UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

GIMP-THREAD-GUIDING MEANS FOR BUTTONHOLE-SEWING MACHINES.

1,372,474.

Specification of Letters Patent. Patented Mar. 22, 1921.

Application filed March 20, 1920. Serial No. 367,298.

To all whom it may concern:

Be it known that I, EDWARD B. ALLEN, a citizen of the United States, residing at Newtown, in the county of Fairfield and 5 State of Connecticut, have invented certain new and useful Improvements in Gimp-Thread-Guiding Means for Buttonhole-Sewing Machines, of which the following is a specification, reference being had there- 10 in to the accompanying drawings.

In sewing a buttonhole, it is customary to lay a filler cord or so-called gimp-thread around the buttonhole and cover it with the overseaming stitches. Heretofore, as illustrated for example in my Patent No. 1,278,817 of September 17, 1918, it has been customary to lead the gimp-thread to the sewing point by passing it through a tubular element arranged within and centrally of the 15 usual rotary turret for the lower stitch-forming instrumentalities. A lower sewing thread is also passed through this tubular element and, to keep the gimp and lower sewing threads from becoming entangled, it 20 was found desirable to employ a separate tube within said tubular element for the lower sewing thread.

The provision of these separate tubes complicates the construction and increases the 30 cost of manufacture. It also necessitates the use of a large axial aperture within the turret, thereby tending to weaken the construction. Furthermore, it is difficult to lead the gimp thread from the upper end of 35 the tubular element to the usual needle-throat while keeping it out of the range of action of the various moving parts of the stitch-forming mechanism mounted on the turret.

40 The present invention has for an object to provide a buttonhole sewing machine with simplified and improved means for guiding the cord or gimp from the source of supply to the sewing point while keeping 45 the cord separated from the lower thread and out of the way of the lower stitch-forming instrumentalities.

In accordance with the present improvement, the gimp is guided externally of the 50 turret to the sewing point, thus entirely removing it from proximity to the lower sewing thread and enabling the hollow turret spindle to be made smaller in diameter and stronger and with a single thread-duct within 55 it. As the turret of the machine is prefer-

ably turned through a complete revolution in sewing around a buttonhole and is then reversely turned to restore it to initial position, a gimp-thread guide is mounted on the frame of the machine in proximity to 60 the turret and at an angular position substantially midway between the extreme angular positions of the turret. The purpose of this arrangement is to enable the gimp-thread given up by the turret during 65 the first half of the sewing cycle to compensate for that required by the turret in turning through the second half of the sewing cycle, whereby no strain will be imposed upon the gimp-thread due to the turning 70 movement of the turret.

In the accompanying drawings Figure 1 is a fragmentary side elevation of a buttonhole sewing machine embodying the invention. Fig. 2 is a front end view, partly in 75 section. Figs. 3, 4 and 5 are plan views of the lower rotary turret of the machine showing the gimp-thread handling mechanism and the lead of the gimp-thread at the beginning, intermediate and final stages of a 80 buttonhole sewing operation, and Fig. 6 is an elevation of the rotary turret and parts carried thereby, looking in the direction of the arrow, Fig. 1.

In the preferred embodiment of the invention, as illustrated, 1 represents the hollow rectangular machine bed from which rises the bracket arm standard 2 for the usual superstructure including the reciprocating eye-pointed needle 3 mounted upon 90 and eccentrically to the needle-bar 4 which, in addition to its reciprocating movements, is turned about its axis in sewing around a buttonhole.

Coöperating with the upper needle 3 is a 95 lower curved and eye-pointed needle 5 fixed in the needle-carrier 6 which oscillates upon the pin 7 at the upper end of the lower needle-supporting post 8 rising from the lower rotary turret 9 having a hollow stem 100 10 which is journaled within the fixed curb or casing 11. Coöperating with the upper and lower needles is the usual looper 12 which seizes a loop of thread from the upper needle below the work and presents it for 105 entry by the lower needle which, in turn, carries a loop of its own thread up through the buttonhole slit and presents it above the work for entry by the upper needle on its next descent. Stitch-forming mechanism of 110

the above type is well known and is disclosed for example in my Patent No. 1,162,207 of November 30, 1915. As the specific character of the stitch-forming mechanism is immaterial to the present invention a further detailed description thereof is deemed unnecessary.

It will be understood by those skilled in the art that the needles 3 and 5 operate through the extremities of the U-shaped aperture 13 in the usual needle-throat or "button" 14 which is mounted upon the post 15, Figs. 2 and 6, rising from the turret 9. The extremity of the U-shaped needle aperture 13 which receives the lower or curved needle is concentric with the center o which represents the axis about which the turret turns. The upper needle 3 is offset from the axis of the needle-bar which is coincident with the axis o ; the needle 3 operating through the other extremity of the U-shaped aperture. The necessary motions are imparted to the lower stitch-forming instrumentalities by means of the usual tubular actuating rod 16 which reciprocates vertically within the hollow spindle or stem 10 of the turret. The actuating connections between the rod 16 and the lower stitch-forming instrumentalities are fully disclosed in my said Patent No. 1,162,207 and as they are well known to those skilled in the art, a detailed description thereof is believed to be unnecessary.

Mounted upon the post 15 is a gimp-thread tension device and guide comprising a plate 17 formed with a thread-eye 18 and threading slit 19. Secured to the inner face of the plate 17 by means of the screw 20 is the lower end of a light leaf-spring 21 the upper or free end of which bears lightly against the inner face of the plate 17 above the thread-eye 18. Also mounted upon the post 15 is one end of a slack gimp-thread controlling spring 22 the free end of which is bent to form a thread-eye 23 through which the gimp passes on its way from the check-spring 21 to the needle-throat 14. A circular guard ring 24 is mounted horizontally upon the curb or casting 11 for the turret 9. This guard ring 24 also assists in guiding the gimp.

The machine is provided with the usual work-clamp 25 and buttonhole cutter levers 26, 27 together with the necessary actuating means which may be and are preferably constructed substantially in accordance with the disclosure of my said patents. A gimp thread pull-off device 28 constructed substantially in accordance with the disclosure of my said Patent No. 1,278,817 is fitted to the side of the machine frame and is operated by the usual cutter-shaft 29.

In the embodiment of the invention illustrated the post 15 which supports the needle-throat 14 is pivotally mounted at 15^a upon

the turret in order that the needle-throat may be tilted forwardly to permit the cutter-levers to move forwardly and cut the buttonhole in stitching position. Mechanism of this type is fully disclosed in my Patents Nos. 1,048,786 and 1,162,207 and is well known to those skilled in the art. When the needle-throat is tilted forwardly to clear the cutters, the spring 22 yields the necessary slack gimp-thread. This slack is subsequently taken up or absorbed by said spring when the needle-throat is restored to sewing position.

The card or gimp-thread g passes from the supply through the pull-off 28, thence forwardly to the guide 30 which is mounted within the front end of the hollow-base 1. From the guide 30 the gimp-thread passes upwardly over the guard ring 24 and through the thread-eyes 18 and 23 to the usual gimp-thread guiding aperture in the needle-throat 14.

Referring to Fig. 3, which represents the turret in initial position, it will be noted that a line $o-a^1$ is drawn from the center of rotation of the turret through the guide-eye 18.

Another line $o-b$ is drawn from the center of rotation through the stationary guide 30. The line $o-a^1$ represents one extreme angular position of the turret relative to the line $o-b$ and will be seen, in the present embodiment of the invention, to be spaced substantially 180° from the line $o-b$. The arrow represents the direction in which the turret will move when the stitching operation is started. As shown in Fig. 3 the gimp g is substantially free from slack.

In Fig. 4 the turret is shown in a position $o-a^2$ substantially midway between its extreme positions. In this position of the turret the gimp-thread is slack and hangs loosely over the guard ring 24. The supporting post 8 for the curved needle serves as a guard to prevent the gimp from being drawn into the paths of the moving parts, particularly during movement of the turret from the position shown in Fig. 4 to that shown in Fig. 5.

In Fig. 5, the turret is shown in final extreme position $o-a^3$ at the end of the stitching operation, having, in the embodiment of the invention illustrated, made one complete revolution. From this position the turret is customarily turned in the reverse direction, as indicated by the arrow, Fig. 5, to restore it to initial position, Fig. 3. A guard 31, secured to the guard ring 24, assists in holding the gimp-thread away from moving parts of the machine.

Having thus set forth the nature, what I claim herein is:—

1. A buttonhole sewing machine having, in combination, overseaming stitch-forming

mechanism including upper and lower stitch-forming instrumentalities, supporting means therefor including a lower rotary turret, and means for guiding a gimp-thread externally of said rotary turret and delivering it at the under side of the work within the range of action of the stitch-forming instrumentalities.

2. A buttonhole sewing machine having, 10 in combination, overseaming stitch-forming mechanism including upper and lower thread - carrying implements, supporting means therefor including a lower rotary turret, means within said turret for guiding a 15 lower sewing thread to the stitch-forming implements, and means external to said turret for guiding a gimp-thread to and delivering it at the under side of the work within the range of action of the stitch-forming 20 implements.

3. A buttonhole sewing machine having, 25 in combination, overseaming stitch-forming mechanism including upper and lower stitch - forming instrumentalities, supporting means therefor including a lower rotary turret formed with a hollow stem, and means for guiding a gimp-thread externally of the stem of said rotary turret and delivering it at the under side of the work 30 within the range of action of the stitch-forming instrumentalities.

4. A buttonhole sewing machine having, 35 in combination, overseaming stitch-forming mechanism including upper and lower stitch - forming instrumentalities, supporting means therefor including a lower rotary turret adapted to be turned on its axis through a definite arc in sewing around a buttonhole and to be reversely turned to initial position after the buttonhole has been stitched, means for guiding a gimp-thread externally of said rotary turret and delivering it at the under side of the work within the range of action of the stitch-forming 45 instrumentalities, and a second gimp-thread guide mounted on the frame at an angular position substantially midway between the extreme angular positions of the turret.

5. A buttonhole sewing machine having, 50 in combination, overseaming stitch-forming mechanism including upper and lower stitch - forming instrumentalities, supporting means therefor including a lower rotary turret adapted to be turned on its axis through a definite arc in sewing around a 55 buttonhole and to be reversely turned to initial position after the buttonhole has been stitched, and means for guiding a gimp-thread externally of said rotary turret and delivering it within the range of action of 60 the stitch - forming instrumentalities, said means including a gimp - thread guide mounted on said turret and a second gimp-thread guide mounted on the frame at an angular position substantially midway between the extreme angular positions of the 65 movable gimp-thread guide relative to the axis of said turret.

6. A buttonhole sewing machine having, 70 in combination, stitch-forming mechanism including, upper and lower stitch-forming instrumentalities, supporting means therefor including a lower rotary turret, a tilting needle-throat mounted on said turret and formed with a gimp-thread guiding aperture, and guiding means for leading the 75 gimp-thread externally of said turret to said aperture, said guiding means including a gimp-thread tension device and slack-thread controller mounted on said turret. 80

7. A buttonhole sewing machine having, 85 in combination, overseaming stitch-forming mechanism including upper and lower stitch - forming instrumentalities, supporting means therefor including a lower rotary turret, and means for guiding a gimp-thread externally of said rotary turret and delivering it within the range of action of the stitch - forming instrumentalities, said guiding means including a guide below the 90 turret and a guard-ring partially embracing the turret and over which the gimp-thread passes to the sewing point.

In testimony whereof, I have signed my name to this specification.

EDWARD B. ALLEN.
